UNITED STATES PATENT OFFICE.

CLARENCE D. KIRTLAN, OF VISALIA, CALIFORNIA.

CULTIVATOR TOOTH.

Application filed April 4, 1923. Serial No. 629,798.

To all whom it may concern:

Be it known that I, CLARENCE D. KIRTLAN, a citizen of the United States, residing at Visalia, county of Tulare, State of California, have invented certain new and useful Improvements in Cultivator Teeth; and I do declare the following to be a full, clear, and exact description of the same, reference being had to the accompanying drawings, 10 and to the characters of reference marked thereon, which form a part of this application.

This invention relates to improvements in that class of agricultural implements known 15 as cultivators, and particularly to the construction and mounting of the teeth; the principal idea being to provide teeth so designed and mounted that they are especially adapted for cultivation in rocky ground, 20 without any chance of bending or breaking the teeth or standards if rocks and the like are encountered which offer great resistance to the forward movement of the cultivator.

I have also provided that any tooth may 25 be easily removed and replaced by another when necessary, without disassembling the entire structure.

A further object of the invention is to produce a simple and inexpensive device and 30 yet one which will be exceedingly effective for the purposes for which it is designed.

These objects I accomplish by means of such structure and relative arrangement of parts as will fully appear by a perusal of 35 the following specification and claims.

On the drawings similar characters of reference indicate corresponding parts in the several views:

Fig. 1 is a top plan view of a cultivator, 40 showing a set of my improved tooth units mounted thereon.

Fig. 2 is an enlarged side view of one of the tooth units, in normal position.

Fig. 3 is a similar view, showing the tooth 45 as mounted when striking a relatively immovable obstruction.

Referring now more particularly to the characters of reference on the drawings, the numeral 1 denotes the main longitudinal and 50 transversely spaced frames of a cultivator, mounted on wheels 2 in the usual manner.

Resting on the frames 1 and bolted there- 55 to are transverse and longitudinally spaced beams 3, which form the supporting means for my improved tooth units, of which there are any desired number. Since these units

are independent members but duplicates of each other, it will of course only be necessary to describe one of the same.

Each unit then consists of a pair of short 60 and transversely spaced bars or frames 4, secured to and under the beams 3, and extending parallel to the frames 1, or longitudinally of the cultivator. Between the beams 3 and 4 a rigid tooth 5, substantially vertical, extends, which is pivoted on the bars 4 as at 6.

On the lower and forward end of the tooth is a removable wearing strip or saddle 7, held in place by a U-clamp 8.

Brackets 9 are pivotally mounted at the upper end of the teeth, in which are adjustably mounted links 10, one on each side of the tooth, between which links and at the lower ends thereof are pivoted bars 11 which 75 extend to the tooth on each side thereof, and are pivotally and slidably mounted thereto by means of a bolt or pin 12 in the tooth passing through longitudinal slots 13 in the bars 11.

Pivots mounted in connection with the bars 4 to the rear of the connection of the tooth therewith are straps 14, which straddle the bars 11 and are pivoted on and between the links 10 intermediate the ends thereof, and preferably just a short distance above the pivotal connection of the bars 11 therewith. A stiff helical compression spring 15 surrounds the bars 11, and extends between the tooth and the straps 14, bearing plates 16 being provided at the ends of the spring 90 between the same and the members 5 and 14, the latter at this point being substantially parallel to the tooth, so as to form a good bearing surface for the adjacent plate. The 95 normal tension of the spring may be regulated by adjusting the nuts 10^a of the links 10.

In operation, the rear edge of the tooth above its pivot 6 normally bears against the 100 adjacent beam 3, preventing forward and upward movement of the lower end of the tooth, the strength of the spring 15, which tends to pull the upper end of the spring back, being sufficient to hold the tooth in 105 the above stated position when the latter is working in ground which offers only a normal resistance to its passage therethrough.

When a rock or the like is encountered 110 however, the tooth is tilted forwardly, and the spring is gradually compressed, increasing the resistance offered by the tooth but

at the same time causing it to be moved into such a position that it is enabled to more readily clear the obstruction, even though it may raise the main frame 1 and rear wheel 5 2 off the ground while so doing. The flexible connections between the tooth, spring and other members causes the spring to be brought into function smoothly and without any shock being imparted to the tooth or 10 frames. It also enables the spring to be compressed in a direct line with its axis at all stages, since the straps 14 remain substantially at right angles to the tooth at all times.

15 To remove any tooth, it is only necessary to withdraw the bolts 6, 12 and the one which holds the bracket 9, when the tooth may be withdrawn in a vertical direction.

Each tooth unit on the cultivator being 20 independent of the other, each will of course function independent of the other.

From the foregoing description it will be readily seen that I have produced such a device as substantially fulfills the objects of 25 the invention as set forth herein.

While this specification sets forth in detail the present and preferred construction of the device, still in practice such deviations from such detail may be resorted to as do not form 30 a departure from the spirit of the appended claims.

Having thus described my invention, what I claim as new and useful and desire to secure by Letters Patent is:

1. A cultivator tooth structure including a 35 supporting frame, a tooth pivoted therein for limited fore and aft swinging movement, straps pivoted on the frame to the rear of the tooth pivot and extending upwardly in spaced relation to the tooth, links between 40 the upper ends of the straps and teeth and pivotally connected to both, and a helical spring between the straps and tooth and arranged for compression when the upper portion of the tooth moves forwardly.

2. A cultivator tooth structure including a supporting frame, a tooth pivoted therein for limited fore and aft swinging movement, straps pivoted on the frame to the rear of the tooth pivot and extending upwardly in 50 spaced relation to the tooth, links between the upper ends of the straps and teeth and pivotally connected to both, bars pivoted to the links below the connection of the straps therewith and extending to slidable connections with the tooth, and a helical compression spring about the bars and bearing at one end against the tooth and at the other end against the straps.

In testimony whereof I affix my signature.

CLARENCE D. KIRTLAN.
